BUILDING WALL CONSTRUCTION UNIT

Russell C. Graef, Westfield, N. J.

Application June 11, 1935, Serial No. 25,987

5 Claims. (CL. 72—45)

This invention relates, generally, to building construction, and the invention has reference more particularly to a novel building wall construction unit for use in the construction of residences, industrial buildings, and other structures.

Heretofore, in the construction of buildings it has been generally necessary to employ considerable labor in placing first the outside wall structure in place, whether this be masonry or wood, and then installing or adding the interior wall construction. This excessive labor cost greatly increases the investment in the building or other structure.

The principal object of the present invention is to provide a novel building wall construction unit that is adapted to be produced at a factory and then shipped to the place of use, the said construction unit not only providing an outside wall for the building or other structure in which it is to be used, but also providing the inner wall of such building, the said building unit having insulating means incorporated therein for preventing the transmission of moisture, noise or heat through the construction unit.

Another object of the present invention lies in the provision of a novel construction unit comprising an intermediate layer of moisture, heat and sound insulating material, and exterior layers of reenforced cementitious material, together with fastening means interconnecting the reenforcement of said exterior layers, said fastening means extending through said intermediate layer and serving to retain said several layers in a unitary whole.

Still another object of the present invention is to provide a novel wall construction unit that is adapted to extend vertically the full height of a single floor so that when the said unit is set in place in use it is not necessary to add additional superimposed units to complete the wall of such floor, the said construction unit thereby requiring the use of but little labor in its installation, which labor may be of the unskilled type.

Still another object of the present invention lies in the provision of the wall construction unit of the above character that is of simple, sturdy and strong construction and which is easily manufactured and conveniently and expeditiously handled in use.

Other objects of this invention, not at this time more particularly enumerated, will be clearly understood from the following detailed description of the same.

The invention is clearly illustrated in the accompanying drawings, in which:

Fig. 1 is a fragmentary perspective view showing a building employing one arrangement of the novel wall construction of this invention.

Fig. 2 is an enlarged fragmentary sectional view taken along the line 2—2 of Fig. 1 looking in the direction of the arrows.

Fig. 3 is a perspective view of one of the wall construction units employed in Figs. 1 and 2.

Fig. 4 is an enlarged fragmentary sectional view taken along line 4—4 of Fig. 1 looking in the direction of the arrows.

Fig. 5 is a perspective view of an interior partition wall used in Fig. 1.

Fig. 6 is a diagrammatical sectional view illustrating the manner of casting the outside wall layer.

Fig. 7 is a view similar to Fig. 6 and shows the manner of attaching the intermediate insulating wall portion or layer.

Fig. 8 is a view similar to Fig. 7, but illustrates the manner of forming the inside wall slab or layer.

Fig. 9 is a view similar to Fig. 8 and illustrates one manner of removing the casting forms.

Fig. 10 is a sectional view of the completed construction unit.

Fig. 11 is a vertical sectional view of a building employing a slightly modified construction of building wall unit, the said view also illustrating the construction of floors employing the features of the present invention.

Fig. 12 is an elevational view of one of the wall units used in Fig. 11.

Fig. 13 is a sectional view taken along the line 13—13 of Fig. 12 looking in the direction of the arrows.

Fig. 14 is a fragmentary perspective view illustrating the manner of placing the top plate or lintel upon the assembled wall units, and

Fig. 15 is a view of the wire fastener used in fabricating the wall of Fig. 11.

Similar characters of reference are employed in said views, to indicate corresponding parts.

Referring now to Figs. 1 to 10 of the said drawings, the reference numeral 1 designates a building employing the novel wall construction units of this invention. As especially illustrated in Fig. 3, the outside wall construction unit, designated as a whole by the reference numeral 2, comprises an outside slab or wall layer 3 that is adapted to extend the full height of a floor of the building, i. e. the full height of a room. Inwardly of the slab 3 there is provided an intermediate slab or layer 4 of insulating material, such as cork, fibre board, rock fibres, etc. In-

45

50

55

55

wardly of the intermediate slab 4 there is provided an inner wall layer or slab 5 which constitutes the inner wall of the building, the said inner wall layer being illustrated in Fig. 3 as formed with an integral coving 6 adjoining its top and a base-board molding 7 adjacent its bottom.

The manner of forming the wall construction unit 2 is especially illustrated in Figs. 6 to 9 and comprises the use of a suitable mold, such as the mold illustrated in dash lines in these figures. This mold is shown as having a bottom plate 8, end plates and similar opposite side plates 9 provided with intermediate projections 10. To produce the construction unit, the outside wall finish is first formed by placing in the bottom of the mold a thin layer 11 of the desired finishing material which may be crushed rock, flaked limestone, or any other suitable building material either mixed or unmixed with wet cement or a cement sand mixture. The upper surface of the mold bottom plate 8 is shown as provided with mutually spaced, longitudinally extending molding strips 12 that serve to form ornamental flutes or grooves in the finished outside wall surface of the unit. It will be apparent that the molding strips 12 may have any desired shape or size depending upon the wishes of the particular user, or these molding strips 30 may be omitted altogether, if a plain, flat exterior wall surface is desired.

Upon the thin layer 11 there is poured a backing 13 of a concrete mixture, preferably employing gravel or cinders as the large aggregate. The backing 13 is adapted to extend in the mold as high as the projections 10, and these projections may be removable, if desired, to enable the ready pouring of the backing 13. The thin finishing layer 11 together with its backing 13 constitute the outside slab 3 of the wall unit. Immediately after pouring the backing 13, and before the same has had a chance to harden, the intermediate insulating layer 4 is overlaid upon the backing 13. This intermediate layer 4 carries a reenforcing rod 14 that is supported from the layer 4 by means of wire staples 15 which are driven through the intermediate layer 4, the bights 16 of these staples 14 serving to support the reenforcing rod 14. As the intermediate layer 4 is placed upon the soft backing 13, the bights 16 of the staples 15 and the reenforcing rods 14 settle or sink down into the body of the backing 13, as shown in Fig. 6, thereby serving to reenforce this concrete backing 13. The intermediate layer 4 is of such width as to fill the space between the projections 10 of the mold, the upper surface of the layer 4 being flush with the upper surfaces of projections 10.

Transverse reenforcing bars or rods 17 are now laid so as to extend crosswise of the mold, as shown in Fig. 8, and the free ends of the wire staples 15 are twisted, as shown at 18, around these rods 17, thereby firmly tying the rods 17 to the rod 14. The inside wall or slab 5 is now cast or poured into the mold, the said slab being formed either of concrete, plaster or a suitable cement mixture.

If a coving, such as the coving 6 of Fig. 3 is to be provided on the inner surface of slab 5, this coving is cast simultaneously with the slab, and the same is true of the base-board molding 7. After the inside and outside slabs 5 and 3 harden, the mold side plates 9 may be removed, as shown in Fig. 9, thereby producing the completed wall construction unit 2, as shown in Fig.

10. The spaces or grooves 19 formed in the edges of the now integral construction unit, provide rabbets for receiving blocks 20 (see especially Fig. 2) of insulating material such as cork, which blocks are adapted to project into the spaces 19 of adjoining construction units.

In use, the foundation wall 21 of the building 1 may be provided with a depression or groove 22 (see Fig. 1) in its upper surface for conformably receiving the lower ends of the construction units 10. 2. In assembling these units to form the building wall, it is merely necessary to set the lower ends of the same into the depression or groove 22, the outside wall slab 3 facing the exterior of the building. The units 2 are preferably of such width as to enable the same to be carried by a couple of men and manually set into place on the foundation wall 21. After setting one of these units in place a block 20 of insulating material, such as cork of the same width as the intermediate insulating layer 4, is inserted into the rabbet or groove 19 of the unit, whereupon another building unit is placed in abutting relation to the first laid building unit, the block 20 also projecting into the rabbet 19 of such building unit, thereby forming a continuous side wall, as shown in Fig. 2.

If desired, the vertical cracks or lines of juncture of adjoining building units 2 can be pointed up with cement or other binder such as a suitable mastic. The building units used at the corners are especially shown in Fig. 2, the said units comprising an outside wall slab 3' of angle shape in cross section, and an inside wall 5' also of angle shape. The inside and outside wall slab 35 reenforcements are interconnected by the staples 15, as previously described. The intermediate insulating slab or layer 4' of the corner building unit is shown as made up of two pieces of insulating material such as cork arranged at right angles. The vertical lines of juncture of the inside slabs 5 may also be pointed up with a plaster, cement or a mastic, if desired.

The reenforcing rods 14 of the exterior slabs 3 preferably project somewhat above the tops of the slabs, as shown in Figs. 1 and 3, to afford means for securing the building plates 24 upon the tops of the units 2, as especially shown in Fig. 1, the said upper projecting ends of rods 14 extending through apertures in plates 24 and being 50 bent over or headed at 14' (see Fig. 1), thereby securing the plates 24 to the units 2.

An interior partition wall, designated 25 in the drawings, (see especially Fig. 5) comprises two inner wall slabs 5 spaced apart by an intermediate insulating slab 4. The manner of casting this intermediate partition wall unit 25 will be apparent after the description already given in connection with the casting of unit 2. As shown in Fig. 5, the inner wall slabs 5 may be formed with 60 covings 6 and base-boards 7, although either or both of these ornamental features may be omitted. The interior wall partition units 25 are assembled or installed in the building in the same manner as the construction units 2, thereby forming complete rooms, as shown in Fig. 1. When the rooms of one floor are complete, it is merely necessary to lay a floor on the tops of the walls thus provided, preparatory to setting up the construction units for forming another floor of the 70 building, the horizontal lines of juncture of the successive floors of building units being closed, if desired, with cement or other material.

The building thus produced is not only exceedingly strong, but is moisture proof, sound proof, 75

and will hold heat better than most forms of building construction. The outside layer or slab 3 with its reenforcement gives great strength to the building and the inside slab 5 also possesses great strength owing to its unitary and reenforced nature, whereas the intermediate layer or slab 4 of insulating material positively prevents passage of moisture, heat and sound between the inner and outer layers. The blocks 20 of insulating material completely block or seal the joints between adjoining construction units, thereby providing a tight wall throughout.

In Figs. 11 to 15 a slightly modified construction of the wall unit is disclosed, the said unit being designated by the reference numeral 26. The construction unit of these figures comprises an outside wall slab 27 made up in the same manner as the exterior wall slab 3, only the wall slab 27 is shown as having additional reenforcement in the form of metal mesh 28 which is preferably interlaced with the reinforcing rod 14. The units 26 are also shown as having two of the reinforcing rods 14 instead of one. In these figures instead of using staples for interconnecting the reenforcement of the outside slab to the inside slab, wire fasteners 29 are used, although it will be apparent that staples could be used, if desired. The wire fasteners have their outer hooked ends 30 engaging the reinforcing rods 14 and their inner ends twisted around the reinforcing 31 of the inner layer or slab 32. This reinforcing 31 is illustrated in these figures as also comprising wire mesh. The intermediate layer 33 is of insulating material, such as cork, just as in the case of the intermediate layer of unit 2. The exterior surface of outside slabs 27 are shown as provided with a single ornamental depression 34 instead of a plurality of grooves.

In the form of the invention shown in Figs. 11 to 15 the interior wall coving 6' is shown as formed as a separate unit and comprises a part of the building plate, designated by the reference numeral 35. This building plate is shown as formed of concrete and is rabbeted at 36 for receiving a wood block 37 to which rafters 38 may be nailed; suitable fasteners 39 being employed to secure the blocks 37 to the plate 35. These plates 35 are provided with vertical apertures 40 into which the free upper ends of reinforcing rods 14 are adapted to project. After mounting the plates 35 upon the building units 26, the apertures 40 are filled with cement, thereby securing these building plates in place upon the units 26.

In these figures, the reinforcing rods 14 are also shown as extending downwardly below the lower ends of slabs 27 for projecting into holes 41 provided in the foundation wall 42 which is illustrated as having a flat top and is not necessarily provided with a groove for receiving the wall units 26. The lower depending ends of rods 14 serve to anchor the unit 26 upon the wall 42. To facilitate the assembly of the units 26, their upper ends are illustrated as provided with recesses 43 for receiving staples 44 which serve to tie the upper ends of adjoining units together, as shown in Fig. 14. These staples may also be provided at the bottoms of units 26, if desired.

In Fig. 11 I have also disclosed floors made up

in accordance with the principles of this invention. These floors comprise upper and lower exterior slabs 45 and 46, respectively, which may be made of a concrete mixture reenforced with wire mesh 46, and reenforcing rods 48 similar to rods 14. Rods 48 are interconnected by wire fasteners 29 which extend through the intermediate insulating layer 49, just as in the previous units 2 and 26. Insulating blocks 20' also serve in the floor construction for sealing the joints of the adjacent floor units 50. These units 50 are adapted to be hand laid upon the supporting foundation and assembled in the same manner as the units 2 and 26.

As many changes could be made in the above construction and many apparently widely different embodiments of this invention could be made without departing from the scope thereof, as defined by the following claims, it is intended that all matter contained in the above description or shown in the accompanying drawings shall be interpreted as illustrative and not in a limiting sense.

I claim:—

1. A building wall construction unit having finished inner and outer wall surfaces comprising, an intermediate layer of insulating material and adjoining exterior layers of cementitious material, said exterior layers having reenforcement therein, and tie links extending completely through said intermediate layer with their end portions engaged around the reenforcement of said exterior layers in anchored relation thereto, to thereby secure said intermediate and exterior layers in united relation, the side edges of said intermediate layer terminating inwardly of the side edges of said exterior layers to provide key receiving recesses, and separable key blocks of insulating material for reception in the opposed key receiving recesses of adjoining building construction units for interconnecting the same and for sealing the joints between said units thereby forming a substantially continuous insulation layer coextensive with the entire wall area formed by said interconnected units.

2. A building wall construction unit, as defined in claim 1, wherein said intermediate layer of insulating material and said key-blocks comprise cork slabs.

3. A building wall construction unit, as defined in claim 1, wherein a portion of the reenforcement of at least one of said exterior layers includes a vertically disposed metallic rod having its upper end portion projecting beyond the upper end of the unit for penetration and retention of a building plate imposed upon the latter.

4. A building wall construction unit, as defined in claim 1, wherein at least one of the exterior layers includes a transverse base molding integral therewith.

5. A building wall construction unit, as defined in claim 1, wherein the reenforcement of one exterior layer comprises vertically disposed metallic rods and the reenforcement of the other exterior layer comprises horizontally disposed metallic rods.

RUSSELL C. GRAEF.
